UNITED STATES PATENT OFFICE.

CARL F. BRENN, EMIL G. JURGENS, AND DENVER C. DUDLEY, OF PORTLAND, OREGON.

LOOSE-LEAF HOLDER.

1,216,062.

Specification of Letters Patent.

Patented Feb. 13, 1917.

Application filed April 26, 1916. Serial No. 93,730.

To all whom it may concern:

Be it known that we, CARL F. BRENN, EMIL G. JURGENS, and DENVER C. DUDLEY, citizens of the United States, residing at 5 Portland, county of Multnomah, State of Oregon, have jointly invented certain new and useful Improvements in Loose-Leaf Holders, of which the following is a specification.

10 Our invention relates to loose leaf holders in general, and particularly to that class of such holders as retain the loose leaves without binding them together.

15 The objects of our invention are to provide a holder for loose leaves, cards, blank checks, receipts and the like, which will securely retain the same without their being bound or secured together before being placed within the holder; to provide in such a holder means 20 for securing the contents therein without any perforations or other devices in or attached to the said contents; to provide such a device as shall be simple in operation and cheap to manufacture.

25 We accomplish the above objects by means of the construction illustrated in the accompanying drawings, which therefore become a part of this application for Letters Patent, like characters of reference indicating like 30 parts throughout the several views, and in which:—

Figure 1 is a perspective view of our invention with the cover shown partially open, and the contents disclosed.

35 Fig. 2 is a perspective view showing the cover closed.

Fig. 3 is a perspective view of the retaining spring.

40 Fig. 4 is a perspective view on an enlarged scale, showing the pockets adapted to receive the spring.

Fig. 5 is a longitudinal sectional elevation showing the spring in place in the pockets.

45 In general our invention consists of a single piece of material folded to form the back, cover, end, and a flap attached to said back; two pieces of material secured to the inner surface of said first piece of material with portions of each left unattached to said first 50 piece of material, whereby said unattached portions are formed into pockets to receive portions of a binding spring.

The first or outer piece of material is folded to comprise a cover 1, a back 2, an end 55 3 intermediate said cover and said back, and a flap 4.

Said flap 4 is attached to the back 2 at the end thereof opposite said end 3, and is adapted to fold over upon said back substantially parallel therewith and toward said end 3, as 60 shown in Figs. 1 and 2.

Upon the inner surface of said back is secured a piece of suitable material 5 having a portion 6 thereof left unattached to said back, said portion 6 being disposed adjacent 65 said flap 4, thus forming a pocket between back 2 and piece 5 opening transversely of said back and toward said flap, as shown in Fig. 4.

A similar piece of material 7 is secured to 70 the inner surface of flap 4, having an unattached portion 8 forming a pocket between said material 8 and said flap 4, said pocket opening transversely of said flap and toward said back, as shown in Fig. 4. 75

It will be observed that the two said pockets open toward one another with a space between them, as shown in Fig. 4, and a spring is provided to be inserted within 80 said pockets and to cause flap 4 to fold over with the transverse edge 10 thereof in juxtaposition with the inner surface of back 2, as shown in Fig. 5.

Said spring is constructed of one piece of material having a bar 11 adapted to be inserted into pocket 8 upon flap 4, each end of 85 said bar being bent substantially normal thereto to form arms 12, said arms being given a loop like bend 13 and thereby extended toward and beyond bar 11 to form 90 ends 14, as shown in Fig. 3, said ends being adapted to be inserted into pocket 6 upon back 2, the spring thus having the position shown in Figs. 1 and 5.

Cards 15, or any material to be contained 95 within the holder may be inserted between the edge 10 of flap 4 and the back 2, when the spring will hold said material securely in place, and the cover 1 may be inserted beneath edge 10 of flap 4 thus securely closing 100 the holder around the contents thereof, as shown in Fig. 2.

Our invention may be made of any size and constructed of any material deemed convenient and suitable for a device of this 105 character, and while we have illustrated and described a form of construction and arrangement of parts found desirable in materializing our invention, we wish to include in this application for Letters Patent 110 all mechanical equivalents and substitutes that fairly be considered to come with-

in the scope and purview of our invention as defined in the appended claims.

Having disclosed our invention so that others skilled in the art may be enabled to construct and use same, what we claim as new, and wish to secure by Letters Patent is:—

1. A loose leaf holder comprising a single piece of material folded to produce 10 a cover, a back, an end portion therebetween, and a flap upon that end of said back opposite said end portion, said flap being turned toward said end portion and substantially parallel to said back; a piece of material 15 secured to the inner surface of said back and having a portion thereof unattached to said back to form a pocket between said material and said back adjacent said flap; a piece of material secured to the inner surface of said 20 flap and having a portion thereof unattached to said flap to form a pocket between said material and said flap adjacent said back; and a spring having one portion thereof adapted to be inserted into one of 25 said pockets, and another portion thereof adapted to be inserted into the other of said pockets, thereby causing said flap to fold

over upon said back with the transverse edge of said flap in juxtaposition to the inner surface of said back.

2. In a loose leaf holder, a back; an end secured thereto; a cover secured to said end; a flap secured to said back opposite said end, and adapted to fold over upon said back substantially parallel thereto and to 35 toward said end; said back and said flap each having formed therein a pocket; and a spring comprising a loop portion disposed intermediate said flap and said back, an extension within the pocket upon said flap, 40 and an extension within the pocket upon said back, and adapted to hold said flap in folded position.

In witness that we claim the foregoing as our own we hereunto place our signatures 45 in the presence of two witnesses in the city of Portland, county of Multnomah, State of Oregon, this 27th day of March, 1916.

CARL F. BRENNE.
